UNITED STATES PATENT OFFICE.

BRUNO HUGO KÖRNER, OF DOHNA, NEAR PIRNA, GERMANY, ASSIGNOR OF ONE-HALF
TO EMIL PIETZSCH, OF DOHNA, NEAR PIRNA, GERMANY.

APPARATUS FOR STOPPING LEAKS, ESPECIALLY IN THE BOTTOM AND SIDE WALLS OF SHIPS' HULLS.

Application filed April 5, 1927. Serial No. 181,210, and in Germany March 31, 1926.

This invention relates to an apparatus for stopping leaks especially in the bottom and side walls of ships' hulls and comprising a spindle guided in the apex of a hood placed onto the part of the side wall or bottom of the ship's hull which has run a leak and covering the circumference of the leak and having an edge that is sealed watertight when pressed against the ship's hull. A hand wheel is fixed on the outer end of the spindle and arms are hingedly fixed on the inner end of the spindle and designed, when said spindle is rotated, to be spread under the influence of draw-stays hingedly connected at the one end to a nut which guides the spindle and at the other end each to one of said arms. The arms are thus pressed onto the inner side of the ship's hull or bottom. An embodiment of the invention is shown, 20 by way of example, on the accompanying drawing, in which

Fig. 1 shows the apparatus in longitudinal section.

Fig. 2 is a similar view, showing the apparatus fixed on the ship's hull.

Fig. 3 is a plan view of Fig. 2.

The apparatus consists of a hood *b* made of convenient material, for instance steel, and having an edge *a* of rubber. In the apex of the hood *b* a screw spindle *c* is screwed. On the outer end of the screw-spindle *c* a hand wheel *d* is fixed. On the inner end of the screw-spindle *c* a collar *f* is mounted on which arms *e* are hingedly fixed. In a nut *g* fixed on the inner surface of hood *b* the screw-spindle *c* is guided and stays *h* are hingedly fixed on said nut. The stays *h* are further hingedly connected at the other end each to one of the arms *e*. On the free 40 ends of each arm *e* a rubber pad *i* is fixed.

The operation is as follows: The hood *b* is placed over the leak *k* on the ship's hull or bottom *l*, so that it completely covers the leak. The arms *e* and the stays *h* and the spindle *c* are in the position shown in Fig. 1. 45 In order to stop the leak the spindle *c* is rotated by means of the hand-wheel *d*, so that it is screwed into the hood *b*. The arms *e* are lifted and spread at the downward movement of the spindle *c* until the pads *i* bear from the inside onto the ship's hull the hood being strongly pulled onto the outer surface of the ship's hull, the rubber edge *a* being compressed. The leak is thus tightly covered and packed. 50

Convenient means may be provided to ensure the spindle against back-rotation.

This apparatus may also be used for stopping leaks in boilers or the like until they can be repaired. 60

I claim:

An apparatus for stopping leaks especially in ships' hulls and bottom, comprising in combination a hood of steel to be placed onto the ship's hull to cover the leak, a rubber 65 packing on the edge of said hood, a screw spindle screwed into the apex of said hood, a hand-wheel on the outer end of said screw-spindle, a nut on the inner surface of said hood and serving to guide said screw-spindle, 70 a collar mounted on the inner end of said screw-spindle, arms hingedly fixed to said collar, a rubber pad on the outer surface of each arm, and stays hingedly fixed at the upper end to said nut and at the lower end to a corresponding arm, substantially as described and shown. 75

In testimony whereof I affix my signature.

BRUNO HUGO KÖRNER.
